PROCESS AND APPARATUS FOR MAKING
DESIGN ROOFINGRichard A. Holdsworth, New York, N. Y., assignor
to The Barrett Company, New York, N. Y., a
corporation of New Jersey

Application October 18, 1933, Serial No. 694,126

10 Claims. (Cl. 91—16)

This invention relates to roofing and more particularly to the production of roofing or siding having the exposed face formed with a desired pattern or design.

5 One of the objects of this invention is to provide a novel method and apparatus for applying viscous bituminous coating material to either plain saturated felt or mineral-surfaced sheet roofing in the form of a pattern or design.

10 Another object of the invention is to provide an improved apparatus and process for applying a design or pattern of coating material having high viscosity or plasticity, such as heavy asphalts, mastics, and filled asphalt coatings, to 15 grit surfaced roll roofing and shingles and thereafter surfacing the viscous or plastic coating material with comminuted material contrasting in color with the grit of the first surfacing.

Another object of the invention is to provide a 20 method and apparatus for applying a design to a sheet of roofing material by positively feeding a relatively thick layer of viscous or plastic bituminous composition through a stencil onto the sheet of roofing.

25 Prior to this invention it was common practice in the roofing industry to apply ornamental designs or patterns to saturated roofing felt or mineral-surfaced roll roofing by contacting the roofing base with a suitable printing roll rotating in a bath of coating material. Such method was particularly adapted for use with materials such as paints and fluid bituminous compositions. Viscous coating materials could not be applied in this manner unless first heated to a high temperature in order to render them fluid. Since a 30 considerable interval was required to cool such material to the setting point, such viscous materials applied at a high temperature usually ran and spread over adjacent uncoated areas of the 35 roofing with the consequent formation of poor designs and defective material.

In the process of the present invention viscous coating material is positively fed through a 40 perforated belt or stencil onto the sheet of roofing. My invention permits the use of relatively viscous materials, such as heavy viscous bitumens, bituminous mastics, and filled asphalt coatings, so that a fairly thick layer can be applied to the 45 roofing and sharply defined designs produced. The thickness of the coating produced in accordance with my invention is controlled by the thickness of the stencil and, by using stencils of desired thickness, well defined coating layers of desired thickness may be formed.

50 For a better understanding of the invention,

reference should be made to the accompanying drawing wherein is shown by way of illustration a preferred method of carrying out the invention and in which:

Fig. 1 is a side elevation, somewhat diagrammatic in character, showing a preferred arrangement of the apparatus;

Fig. 2 is a fragmentary plan view of the finished sheet showing one type of design roofing which may be produced by this invention;

Fig. 3 shows the type of perforated endless belt used in producing the roofing of Fig. 2;

Fig. 4 is a fragmentary enlarged vertical section taken along the line 4—4 of Fig. 2 showing the design applied to a grit-surfaced base; and

Fig. 5 is a fragmentary enlarged vertical section of a finished sheet showing the design applied to a plain saturated felt base.

Referring to the drawing, with particular reference to Fig. 1, numeral 1 denotes a sheet of 20 grit-surfaced roofing, as for example, felt saturated with asphalt, coated on both sides with asphalt, surfaced on the top side with grit, and having mica applied to the seal-back coating on the under side. Surfaced sheet 1 is fed from a 25 suitable source of supply over guide rolls 2 and 3 and contacts with an endless perforated belt 5, which may be of steel or other flexible durable material. The belt passes around spaced rollers 7 and 8 driven at any desirable speed through 30 a suitable drive (not shown). As shown in Fig. 1, the spaced rollers and endless belt are adapted to move in a counter-clockwise direction. Between the spaced rollers is a rotating coating roll 10 which abuts tangentially against the inner 35 face of the endless belt passing thereover.

Coating roll 10 is rotatably mounted in tank or coating pan 12 which may contain heavy viscous coating material, such as heavy bituminous compositions or bituminous mastics. The roll preferably moves in a direction opposite to the movement of the endless belt and spaced rollers, i. e., it rotates in a clockwise direction. Positioned above the coating pan is a scraping device 14 which contacts with the inner surface of the 45 stencil after it passes over the coating roll and returns excess coating material from the stencil to the pan.

Before being brought into contact with the sheet of roofing 1, the perforated belt is first 50 given an application of anti-stick solution, such as a solution of soap and water. This solution may be applied by means of a suitable application roll 15 positioned below roller 8 and contacting with the outer surface of the perforated belt as it 55

passes around the roller. Application roll 15 is rotatably mounted in a tank or container 16 for holding the anti-stick solution. The anti-stick solution prevents the belt from sticking to the 5 viscous coating material and permits the ready separation of the belt or stencil from the coated sheet thereby insuring the production of a clean-cut design or pattern.

After the grit-surfaced sheet is contacted with 10 the perforated belt 5, they pass together horizontally over coating roll 10. Rotation of the coating roll in the coating pan causes a layer of coating material to adhere to the surface of the coating roll. As the perforated belt and sheet 15 of roofing pass over and contact with the roll, the roll forces the coating material through the perforations in the belt onto the surface of the sheet in a desired pattern or design. After the coating operation, scraper 14 removes any excess coating 20 material from the endless belt and returns it to the coating pan 12.

When the endless belt and sheet of roofing reach roller 7, the belt is stripped from contact 25 with the coated sheet and passes downwardly around the roller and thence back to roller 8. The coating material which was forced through the perforated belt remains on the surfaced sheet and forms a design, the exact configuration of which depends upon the perforations or open 30 spaces in the belt. The coated sheet passes around reversing roll 18 disposed directly over roller 7.

After leaving reversing roll 18 and while the 35 viscous coating material is still in a tacky condition, the coated sheet passes under a surfacing device or hopper 20 extending across the width of the sheet. Granular surfacing material, such as crushed stone, crushed slate, or other mineral or non-mineral grit, is fed into this hopper and is 40 showered by means of the usual distributing roll 21 onto the coated base passing thereunder. The thus surfaced sheet then passes about reversing roll 24 which functions to partially embed the 45 granules of surfacing material in the plastic coating material. Any granules which may fall on the previously surfaced portions of the sheet surrounding the coated areas do not adhere thereto. When the sheet leaves reversing roll 24 such 50 granules and the excess granules on the coating layer fall back therefrom into feed hopper 20.

It is obvious that the above described procedures 55 make it possible to form roll roofing having a wide variety of designs or patterns. The exact design obtained depends entirely upon the type of perforated belt used.

Fig. 3 shows a type of perforated belt which 60 may be used to form the brick-simulating roofing shown in Figs. 2 and 4. This belt is composed of a series of parallel metal bands 26 connected together by perpendicular metal bands 27 65 forming rows of brick shaped openings or perforations 29. The narrow horizontal and vertical depressed areas 31 and 32 on the sheet are formed by the bands 26 and 27 respectively of the 70 perforated belt. The rectangular brick shaped areas 33 defined by the depressed areas correspond to the open portions or perforations in the belt. The thickness of the coating material applied to the sheet depends chiefly upon the thickness of the perforated belt.

A single coated product having an appearance 75 similar to that shown in Fig. 3 may be prepared by using plain saturated felt or saturated roll roofing in place of the grit surfaced roofing as described above. When operating with plain

saturated felt, it is often desirable to apply a seal-back coating of cementitious bituminous material to the underside of the sheet, either before or after applying the design coating, and then rendering the seal-back coating non-cementitious 5 by the application of a suitable anti-stick composition such as mica flakes or powdered talc. Fig. 5 is a fragmentary enlarged section through a finished sheet made in this way and shows the design coating applied directly onto the saturated 10 sheet.

The present invention makes it possible to apply coating material in highly viscous or plastic condition in well defined designs to roofing resulting in the production of roofing of ornamental appearance and improved weathering properties. This feature is made possible by the fact that the coating material is forced through the interstices of the endless belt or stencil by the positive action of the coating roll against the 20 surface of the belt. Relatively high melting point asphalt of a melting point from 85° C. to 120° C. and preferably about 105° C. may be applied by this method at a temperature ranging from 150° C. to 235° C. Bituminous mastics and filled asphalt coatings containing considerable quantities of inert material, such as asbestos, wood flour, sand, etc., may also be employed. For example, I may use a mastic containing 70% asphalt and 20% cork and 10% mica and having a 30 specific gravity of about 0.8, or a mastic containing 45% asphalt and 40% sand and 10% mica and having a specific gravity of about 1.4.

Since certain changes in carrying out the above process and in the constructions set forth may 35 be made without departing from the scope of this invention, it is intended that all matter contained in the above description or shown in the accompanying drawing shall be interpreted as 40 illustrative and not in a limiting sense.

I claim:

1. The process of forming ornamental design roofing comprising contacting a roofing sheet with a stencil of substantial thickness, forcing viscous coating material through the perforations in the stencil onto the sheet to form thereon raised portions of substantial height and depressed portions of substantial depth thereby giving an embossed appearance to the sheet and retaining the stencil in contact with said sheet until said coating material has partially hardened.

2. The process of applying molten asphalt of a melting point from 85° C. to 120° C. heated to a temperature considerably above its melting point to a sheet of roofing in a predetermined design, 45 comprising contacting the sheet with a perforated belt composed of material such that it will withstand without decomposition or rupture the temperature to which the asphalt is heated, pressing the asphalt through the perforations in the belt 50 onto the sheet and retaining the perforated belt in contact with said sheet until said asphalt has partially hardened.

3. The process of applying a design of coating material in a viscous condition to a roofing base, 65 said coating material being of relatively high melting point and heated to a temperature substantially above its melting point, comprising placing a stencil in contact with the base, forcing viscous coating material up through the stencil 70 onto the overlying base, retaining the stencil in contact with the base until the coating material has partially hardened, and removing the stencil from contact with the base.

4. The process of coating sheet roofing in pre-

determined design by forcing viscous coating material of relatively high melting point and heated to a temperature above its melting point through a stencil of substantial thickness onto the sheet, 5 which comprises contacting the stencil with the sheet, supplying viscous coating material to the stencil, applying pressure to the viscous coating material to force it through the stencil onto the sheet to form raised coated portions of substantial height separated by depressed portions of 10 substantial depth, retaining the stencil in contact with the base until the coating material has partially hardened, removing the stencil from the coated sheet, and partially embedding surfacing material in the raised coated portions of the sheet. 15

5. The process of applying a thick layer of high melting point viscous coating material in a predetermined design to mineral surfaced sheet roofing by forcing the viscous coating material 20 heated to a temperature above its melting point through a stencil onto the surfaced sheet, which comprises superimposing the sheet on the stencil, supplying viscous coating material to the underside of the stencil, applying pressure to the viscous coating material to force it through the stencil onto the sheet, retaining the stencil in contact with the sheet until the viscous coating material has partially hardened, and removing the coated sheet from contact with the stencil. 25

6. Apparatus for applying a design of viscous high melting point waterproof bitumen heated to a temperature above its melting point to sheet roofing comprising a stencil constructed of material capable of withstanding the temperatures 30 and stresses imposed by the application of the heated bitumen, and a coating roll arranged to supply viscous coating material to the stencil and force it therethrough.

7. Apparatus for applying a relatively thick 35 layer of coating material in ornamental three-dimensional relief design to a sheet of roofing material comprising in combination an endless stencil of substantial thickness, and a coating roll disposed beneath the stencil and adapted to contact therewith, said coating roll forcing the coating material through the stencil to form an ornamental design composed of raised portions of substantial height and depressed portions of substantial depth, the difference in thickness be- 40

tween said raised and depressed portions being substantially equal to the thickness of said stencil.

8. Apparatus for applying high melting point 45 bituminous material in a predetermined design constituted of raised and depressed portions of substantial height and depth respectively to a sheet of roofing material, said apparatus comprising spaced rollers, an endless perforated metal belt of substantial thickness adapted to move around said rollers, and a coating roll disposed between said rollers and abutting against the inner face of the perforated belt, a source of said bituminous material, said coating roll forcing the bituminous material from said source through the 10 perforations in said belt to form a design constituted of raised and depressed portions, the difference in thickness between said raised and depressed portions being substantially equal to the thickness of said belt. 15

9. Apparatus for applying heated, viscous, relatively heavy bituminous material to a sheet of roofing in a predetermined ornamental design, comprising spaced rollers, an endless metal stencil of substantial thickness adapted to pass around 20 said rollers, means for contacting a sheet of roofing with the outside surface of said stencil, a coating roll disposed between said rollers in contact with the inside surface of said stencil, said coating roll being adapted to supply viscous bituminous material to the stencil and to force it therethrough onto the sheet of roofing to form a design composed of raised portions of substantial 25 height and depressed portions of substantial depth, the difference in thickness between said raised and depressed portions being substantially equal to the thickness of said stencil. 30

10. The process of making roofing having a predetermined three-dimensional relief design which comprises forcing heated viscous coating 40 material onto a roofing base through a stencil of substantial thickness to form on said base raised portions of substantial height and depressed portions of substantial depth thereby giving an embossed appearance to said roofing and retaining 45 the stencil in contact with said base until the coating material has partially hardened.
